JOURNAL BOX LID AND SPRING ASSEMBLY

Carl J. Touhey, Lakewood, Ohio, assignor to
Moline Iron Works, Moline, Ill., a corporation
of Illinois

Application September 25, 1948, Serial No. 51,187

4 Claims. (Cl. 308—47)

1

This invention relates to a journal box lid and spring shoe assembly of the type in which the lid is provided with a spring pressed shoe adapted to bear against a cam face formed on the journal box hinge lug and serving to hold the lid in open or closed position and to maintain a substantial pressure on the lid when it is in closed position.

The principal objects of the present invention are to provide a simple and relatively inexpensive lid and spring shoe assembly which is so constructed that the spring and the lug engaging shoe are within the lid, and to provide a retainer for the spring shoe that is accessible from the exterior of the lid for holding the spring shoe in a retracted position where it is clear of the hinge lug during the mounting of the lid on the journal box, and which is operable to release the shoe into engagement with the cam face of the lug after the lid is mounted, the retainer being permanently mounted upon the lid and being engageable with the shoe to retract the same from the hinge lug to facilitate the removal of the lid from the journal box.

With the above and other objects in view, the invention may be said to comprise the journal box lid and spring shoe assembly as illustrated in the accompanying drawings and hereinafter described, together with such variations and modifications thereof as will be apparent to one skilled in the art to which the invention pertains.

Reference should be had to the accompanying drawings forming a part of this specification, in which:

Figure 1 is a front elevation of the lid;

Fig. 2 is a vertical section through the lid showing the same mounted on a journal box, and the shoe held by its retainer in retracted position;

Fig. 3 is a fragmentary vertical section showing a shoe detached from its container and engaging the cam surface of the hinge lug;

Fig. 4 is a fragmentary vertical section showing the lid in partially open position with the shoe in engagement with the high point of the cam and in a position to be engaged by the retainer screw by which it may be retracted from cam engaging position to facilitate removal of the lid from the journal box;

Fig. 5 is a fragmentary horizontal section through the shoe showing the threaded opening to receive the spring retracting screw; and

Fig. 6 is a transverse section showing the spring retaining lugs.

In the accompanying drawings the lid and spring shoe assembly of the present invention is shown applied to a journal box 1 of conventional

2

construction which has its walls provided with flat front end edges 2 around the journal box opening. At the top of the journal box centrally over the opening there is a hinge lug 3 provided with a pintle opening 4. The hinge lug 3 also serves as a cam and has a front face 5 and a top face 6 that converge to the high point 7 of the cam.

The present invention is a lid and spring shoe assembly adapted to be mounted upon the journal box, the lid closing the opening of the journal box and the shoe bearing against the cam faces of the hinge lug to hold the lid in a closed or an open position.

As herein shown, a lid 8 which may be in the form of a casting has a flat inner face 9 adapted to bear against the edges 2 of the journal box walls which surround the journal box opening, the inner face 9 of the lid having a stiffening rib 10 within and adjacent the sides and bottom of the journal box opening. The lid 8 has inwardly projecting hinge lugs 11 adjacent its top that are adapted to straddle the journal box lug 3 and that are provided with the pintle receiving openings 12 adapted to register with the pintle opening 4 of the journal box lug. Flanges 13 formed integrally with the lugs 11 extend downwardly therefrom and engage with the opposite end faces of the lug 3 and with the top of the journal box 1.

Adjacent the top of the lid and between the hinge lugs 11 the lid is recessed to provide a shoe receiving pocket 14 that is provided with a top wall 15 that is extended to provide a flange that

engages the top face 6 of the hinge lug 3 when the lid is in closed position, the pocket 14 having a front wall 16 offset outwardly from the body of the lid. The pocket 14 is positioned in front of the hinge lug 3 of the journal box when the lid is in closed position and extends a short distance below the top wall of the journal box. Adjacent the lower end of the pocket 14 spaced apertured spring supporting lugs 17 are provided on the inner face of the lid 8.

The front wall 16 of the pocket 14 is provided with a central opening 18 in which a screw 19 is rotatably mounted. The screw 19 has a head 20 that is adapted to bear on the outer face of the wall 16 around the opening 18. Inwardly of the wall 16 the screw 19 has a collar 21 attached thereto and a coil spring 22 surrounding the screw 19 is interposed between the collar 21 and the inner face of the front wall 16. The spring 22 exerts an inward thrust on the screw 19 to normally hold the head 20 against the outer face of

55

the wall 16 to close the opening 18, as shown in Fig. 3.

A spring having an upwardly extending arm 23 is mounted in the pocket 14 and this spring is formed from spring wire and the arm 23 is formed by the central portion of the wire which is bent to U-shape. The arms of the U are coiled to provide spring coils 24 within the lower portion of the pocket 14 inwardly of the arm 23 and the ends 25 of the arms extend downwardly into the apertured retaining lugs 17. The ends 25 of the spring form a downwardly extending arm exerting an inward thrust on the lid 8. The upwardly extending arm 23 carries a sheet metal shoe 26 which is bent over the upper end of the arm 23 to provide an inner portion 27 overlying the inner face of the arm 23 and adapted to bear against the cam faces of the hinge lug 3.

The shoe has an outer portion 28 overlying the outer side of the arm 23 and the inner and outer portions 27 and 28 of the shoe are fastened to the arm 23 by means of integral tongues 29 which are bent around the side portions of the U-shaped arm 23. The outer portion 28 of the shoe has a reinforcing plate 31 attached to the inner side thereof and a screw threaded opening 32 is formed through the plates 28 and 31. The opening 32 of the shoe is substantially aligned with the opening 18 in the front wall 16 of the shoe pocket and a screw 19 is adapted to be screwed into the threaded opening 32 to draw the shoe 26 and the spring arm 23 toward the front wall 16 to a position where the cam engaging portion 27 of the shoe is clear of the hinge lug 3 so that the spring shoe does not interfere with the mounting of the lid of the journal box.

After the hinge pintle is in place in the lugs 3 and 11 the screw 19 may be turned in a direction to screw out of the hole 32 so as to release the shoe into engagement with the cam face 5 of the hinge lug 3 as shown in Fig. 3. When so released the spring exerts a strong inward thrust on the lid 8 when the lid is in closed position, and when the lid is swung to open position the spring shoe 26 rides over the high point of the cam into engagement with the top cam face 6, in which position the spring arms 25 exert an upward thrust on the lid to hold it in open position.

When the shoe is released from the retaining screw as shown in Fig. 3, the screw 19 is held by the spring 22 with its head 20 in engagement with the outer face of the wall 16 to seal the opening 18 so as to prevent entry of dirt and moisture into the spring shoe pocket.

If it is desired to remove the journal box lid the lid may be swung to the intermediate position shown in Fig. 4 where the shoe 26 bears against the high point 7 of the cam, in which position the inner end of the screw 19 engages in the threaded opening 32 so that by turning the screw 19 by means of a screw driver engaging the head 20, the screw may be entered into the shoe to draw the shoe to a position clear of the hinge lug 3 so that the hinge pintle can be readily removed and the lid detached from the journal box.

It is to be understood that in accordance with the provisions of the patent statutes variations and modifications of the specific devices herein shown and described may be made without departing from the spirit of the invention.

What I claim is:

1. A lid and spring shoe assembly for use on a journal box having an end opening and a hinge lug with converging front and top faces forming a cam whose high point is at the juncture of said

faces comprising a lid having hinge lugs adapted to straddle the journal box hinge lug and a shoe receiving pocket adjacent the top thereof that has an outer wall spaced outwardly from the lid hinge lugs and provided with an opening, a shoe in said pocket for engagement with said cam and movable toward and away from said wall, said shoe having a threaded opening substantially aligned with the opening in the wall, a spring pressing said shoe inwardly away from said outer wall, a screw rotatably mounted in said wall opening and having a head engageable with the outer face of said wall, said screw being adapted to be screwed into the opening of said shoe to shift said shoe toward said wall and out of cam engaging position to facilitate mounting of the assembly on the journal box and to be screwed out of the shoe opening to release the shoe into engagement with the cam after the assembly is mounted on the journal box, and means for retaining said screw in said wall opening comprising a collar attached to the screw and positioned within said wall.

2. A lid and spring shoe assembly for use on a journal box having an end opening and a hinge lug with converging front and top faces forming a cam whose high point is at the juncture of said faces comprising a lid having hinge lugs adapted to straddle the journal box hinge lug and a shoe receiving pocket adjacent the top thereof that has an outer wall spaced outwardly from the lid hinge lugs and provided with an opening, a shoe in said pocket for engagement with said cam and movable toward and away from said wall, said shoe having a threaded opening substantially aligned with the opening in the wall, a spring pressing said shoe inwardly away from said outer wall, and a screw permanently and rotatably mounted in said wall opening, said screw being adapted to be screwed into the opening of said shoe to shift said shoe toward said wall and out of cam engaging position to facilitate mounting of the assembly on the journal box and to be screwed out of the shoe opening to release the shoe into engagement with the cam after the assembly is mounted on the journal box, said shoe being positioned with its threaded opening in position to receive said screw when said shoe engages the high point of the cam so that said shoe may be retracted from the cam to facilitate dismounting of the assembly.

3. A lid and spring shoe assembly for use on a journal box having an end opening and a hinge lug with converging front and top faces forming a cam whose high point is at the juncture of said faces comprising a lid having hinge lugs adapted to straddle the journal box hinge lug and a shoe receiving pocket adjacent the top thereof that has an outer wall spaced outwardly from the lid hinge lugs and provided with an opening, a shoe in said pocket for engagement with said cam and movable toward and away from said wall, said shoe having a threaded opening substantially aligned with the opening in the wall, a spring pressing said shoe inwardly away from said outer wall, a screw extending through said opening and adapted to be screwed into or out of the threaded opening of the shoe, said screw having a head engageable with the outer face of said wall around said wall opening, and a spring exerting an inward pressure on said screw to hold said head in engaging position when the screw is disengaged from said shoe.

4. A lid and spring shoe assembly for use on a journal box having an end opening and a hinge

lug with converging front and top faces forming a cam whose high point is at the juncture of said faces comprising a lid having hinge lugs adapted to straddle the journal box hinge lug and a shoe receiving pocket adjacent the top thereof that has an outer wall spaced outwardly from the lid hinge lugs and provided with an opening, a shoe in said pocket for engagement with said cam and movable toward and away from said wall, said shoe having a threaded opening substantially aligned with the opening in said wall, a spring pressing said shoe inwardly away from said outer wall, a screw extending through said opening and adapted to be screwed into or out of the threaded opening of the shoe, said screw 15

having a head engageable with the outer face of said wall around said wall opening, a collar on said screw inwardly of said wall, and a spring interposed between said collar and said wall.
